UNITED STATES PATENT OFFICE.

JOHN CHARLES DOWD, OF NEW YORK, N. Y.

DESIGN FOR A SMOKER'S SET.

SPECIFICATION forming part of Design No. 20,209, dated October 21, 1890.

Application filed July 18, 1890. Serial No. 359,225. Term of patent 3½ years.

To all whom it may concern:

Be it known that I, JOHN CHARLES DOWD, a citizen of the United States, residing at New York, in the county of New York and State of New York, have invented a certain new and original Design for Smokers' Sets, of which the following is a full, clear, and exact specification, reference being had to the accompanying drawing, forming a part thereof, and which shows in perspective a smoker's set ornamented in accordance with my design.

The leading and most prominent feature of my design consists of the ornamentation of the box or base portion. At the bottom of this is a band consisting of repeated foliate figures *a*. Above this band is a narrower band *b*, consisting of a repeated sinuous ornamentation. Above this last-named narrow band is a line of open-work *c*, above which the top of the box (marked *d*) appears in strong

contrast with the lower portion thereof. The top of the box (lettered *e*) again presents a contrast with the sides of the box. Said top of the box is depressed, and the sides of the depression, as seen at *f*, curve downward and inward and are ornamented with figures in relief. The top just described is designed to support cups or vases *g*, which are preferably ornamented in harmony with the general ornamentation of the box itself. 25 30

I claim—

The design for smokers' sets, substantially as herein shown and described.

In testimony whereof I affix my signature in presence of two witnesses.

JOHN CHAS. DOWD.
